2 Claims

ABSTRACT OF THE DISCLOSURE

An amusement apparatus comprising a base member having disposed centrally thereof a device for delivering to a remote point on said member a series of differently colored and numbered markers, a plurality of spaced playing boards extending radially outwardly from said device, each of said boards having means for holding said markers thereon, and one board also having a counting means thereon, other members having counting means thereon carried by said base member on opposite sides of said one board, and a spinner-type chance device mounted above the marker delivering device. The markers are distributed among the playing boards in accordance with playing rules, and the several counting means are adjusted according to the relative values of the markers so distributed. Indicia applied to the several parts of the apparatus are such that the results of its use may arbitrarily be assumed to indicate the health and wealth status of the user, and the spinner is then used to select by chance factors which are arbitrarily designated as the causes of any deficiency of such status.

This invention relates to amusement devices, and more particularly to an amusement device involving both skill and chance.

One object of the instant invention is to provide an amusement device which will entertain individuals of all ages either separately or simultaneously.

Another object of the instant invention is to provide an amusement device using a plurality of numbered spherical markers.

A still further object of the instant invention is to provide an amusement device having a means of randomly dispensing a plurality of numbered spherical markers.

A further object of this invention is to provide an amusement device having a delivery chute for delivering to a player a single numbered spherical marker.

A further object of this invention is to provide an amusement device having a delivery chute for delivering a single numbered spherical marker to a player in conjunction with a door means for selectively precluding the dispensing of spherical markers.

A still further object of this invention is to provide an amusement device having a means for randomly distributing a plurality of spherical markers and a means for conveniently returning spherical markers to the random distribution means.

Other objects and advantages of this invention reside in the combinations of elements, arrangements of parts, and features of construction and utilization, all as will be more fully pointed out hereinafter and disclosed in the accompanying drawings wherein there is shown a preferred embodiment of this inventive concept.

In the drawings:

FIGURE 1 is a top plan view of the board of the instant invention;

FIGURE 2 is a top view of the center of the board of FIGURE 1, certain parts being removed for clarity of illustration;

2

FIGURE 3 is a partial cross sectional view of the board of FIGURE 1, taken along line 3—3 and viewing in the direction of the arrows;

FIGURE 4 is another partial cross sectional view of the board of FIGURE 1, taken along line 4—4 and viewing in the direction of the arrows showing the random distribution means and the delivery chute; and

FIGURE 5 is a further partial cross sectional view of the board of FIGURE 1, taken along line 5—5 thereof and viewing in the direction of the arrows, showing the random distribution means and the device for returning the spherical markers thereto.

Referring now to the drawings in detail, wherein like reference characters designate like elements throughout the several views thereof, there is indicated generally at 10 a board having a horizontal planar base 12, which may be of any desired configuration, but which is indicated as pentagonal, and a centrally disposed panel, shown generally at 14, which may be of any desired configuration, but which is also illustrated as pentagonal, secured to the center of base 12. A plurality of arms 16, 18, 20, 22 and 24 extend outwardly from the sides of pentagonal panel 14 and are preferably slightly downwardly inclined therefrom as shown in FIGURES 3, 4 and 5.

Supporting panel 14 and arms 16, 18, 20 and 22 are a series of vertical substantially identical trapezoidal beams 26 secured to base 12 in any conventional manner, such as by screws 28 or by nails or glue. As shown in FIGURE 3, arms 16, 18, 20, and 22 are fixed to beams 26 by a plurality of screws 30 with panel 14 resting on exposed edges of beams 26.

Supporting arm 24 and the remaining edge of pentagonal panel 14 are a pair of vertical spaced apart trapezoidal beams 32, 34 which are secured to platform 12 in a similar manner and are fixed to arm 24 by a pair of screws 36 or the like. As more fully explained hereinafter, the slot formed between beams 32, 34 provides a delivery chute shown generally at 38 and including a ramp 40 secured to base 12 as by frictional fasteners 42 and whose inner end is substantially aligned with the inner edges of trapezoidal beams 32, 34.

Positioned interiorly of arms 16, 18, 20, 22, 24 and beneath panel 14 is a distribution means shown generally at 44 which is arranged to deliver a plurality of numbered spherical markers 46 into delivery chute 38 in a randomly selected manner. Distribution means 44 includes a bearing 48 imbedded in platform 12 and having a conical bearing surface 50 in which resides a vertical rotatable post 52 having a conical end 54 received in bearing surface 50. Vertical post 52 slidably carries a circular disc shown generally at 56 having an upper surface 58 which is inclined downwardly along a radial line of disc 56 to allow a spherical marker 46 to gravitate to the outer periphery of disc 56 for purposes more fully explained hereinafter.

A vertical apertured collar 60 is secured to the center of disc 56 and receives vertical post 52 as may be seen in FIGURES 3 to 5. A limit means shown generally at 62 is secured to the underside of disc 56 and includes an enlarged circular plate 64 providing a slot 66 across a diameter. Limit means 62 also includes a rod 68 secured perpendicularly to vertical post 52 and which resides in slot 66 for securing together rotatable post 52 and disc 56. The rod 68 also precludes any downward sliding movement of disc 56 upon shaft 52.

Distribution means 44 also includes a circular wall 70 coaxial with disc 56 and extending above upper surface 58 thereof as seen in FIGURES 3 to 5. Circular wall 70 has a slot 72 between trapezoidal beams 32, 34 to allow for the movement of spherical marker 46 from disc 56 to ramp 40 of delivery chute 38 as seen in FIGURES 2 and 4. Accordingly, the peripheral edge of disc 56, the lower sur-

face of slot 72 and the inner end of ramp 40 are substantially coplanar.

Panel 14 includes a pentagonal base 74 on the upper surface of which is located a series of indicia 76, the importance of which will be explained hereinafter. Secured at the approximate center of base 74 is a depending collar 78 having an aperture 80 slidably received on rotatable shaft 52. It should be seen that collar 78 and base 74 provide an upper bearing surface for rotatable post 52 thus keeping it in a substantially vertical position at all times.

Secured to the upper end of post 52 is a balanced pointer shown generally at 82 which, as illustrated, is provided with four arms 84, one of which is distinctively shaped, as may be seen in FIGURE 3, to provide a means of randomly selecting indicia 76 on base 74 as more fully explained hereinafter. Pointer 82 is provided with a central hub 86 from which arms 84 extend. The upper end of post 52 is formed with a pair of perpendicular slots 88 which receive the arms 84.

As more fully explained hereinafter, one of the features of the amusement device of the instant invention resides in the selection and utilization of numbered spherical markers 46. Markers 46 are placed on disc 56 of distribution means 44 and will gravitate to the periphery of disc 56 because of downwardly sloping upper surface 58. A person playing the amusement device of the instant invention may rotate pointer 82 to sequentially deliver a plurality of spherical markers 46 to delivery chute 38. To preclude markers 46 from rolling down ramp 40 and off platform 12, a stop 90 is positioned between trapezoidal beams 32, 34 as seen in FIGURES 1 and 4.

There are instances when it is desired to preclude the entry of spherical markers 46 into delivery chute 38, such as when the board 10 is being stored. It may also be desirable to close the entrance to the chute 38 when the spherical markers 46 fill the same during play. In order to accomplish this result a door means shown generally at 92 is provided having an L-shaped arm 94 including a suitable handle 96. L-shaped arm 94 is pivotally mounted on arm 24 by a pivot means shown generally at 98 including a collar 100 seatably receiving a helical spring 102 on the face thereof and a bolt 104 which is secured to arm 24 by a nut 106. L-shaped arm 94 has attached on the short leg thereof a vertical door 108 which normally resides at the entrance to delivery chute 38 to preclude the movement of a spherical marker down ramp 40. Trapezoidal beam 32 is cut away on the inner end thereof to form a slot 110 into which door 108 may swing when arm 94 is rotated in a counter-clockwise direction about pivot means 98 as may be seen in FIGURE 2.

A delivery means shown generally at 112 provides a convenient device for delivering spherical markers 46 into distribution means 44 and includes a ramp 114 sloping toward the center of base 12 and supported from base 12 by a vertical trapezoidal beam 116. As seen in FIGURE 5, the inner end of ramp 114 is coplanar with and juxtaposed to the upper edge of circular wall 70. When markers 46 are placed on ramp 114, they will gravitate into distribution means 44 as seen in FIGURE 5.

Fixed on platform 12 between arms 16 and 24 is a rating board shown generally at 118 having indicia 120 thereon indicating the wealth status of the player of the instant game. Rating board 118 includes a substantially rectangular block 122 extending from trapezoidal beam 26 of arm 16 to trapezoidal beam 32 and accordingly defines with said beams and said base a storage area 124 for the reception of spherical markers 46 after they have been used in the play of the game. Rating board 118 is provided with a plurality of indentations 126 associated with indicia 120 into which a pegged marker may be placed as more fully explained hereinafter. Rating board 118 also includes a plurality of hemispherical indentations 128 for purposes more fully explained hereinafter.

A rating board 130 is positioned on base 12 and is provided with indicia 132 indicating the health status of the

player. Rating board 130 includes a rectangular block 134 having a series of indentations 136 associated with indicia 132. Block 134 is also provided with a series of hemispherical indentations 138 as more fully explained hereinafter.

5 A good deal of the play of the instant amusement device is conducted on arm 24 which is provided with a plurality of indentations 140 for receiving spherical markers 46. Arm 24 also includes three separate strips 142, 144, 146 providing indentations 148 to receive pegged markers. Three indentations 150, 152, 154 are also provided to receive a plurality of smaller spherical markers which represent ambition, talent and grace, as more fully explained hereinafter. Another series of indentations 156 is provided to receive markers which correspond to disability points which is also explained hereinafter.

In the play of the amusement device of the instant invention, a plurality of spherical markers 46 are provided, preferably four series numbered from one to ten, 20 each series being distinctively colored. Three special markers, one suitably inscribed to indicate a talent marker and the remaining two suitably inscribed to indicate disability markers are also provided, with all markers being placed in distribution means 44. Suitable pegged markers 25 are positioned in the lowermost apertures 148 of strips 142, 144, 146.

The first step in the play of the amusement device is to allow a plurality of numbered spherical markers 46 to descend into delivery chute 38, the first marker resting 30 against stop 90. Two markers will be removed from chute 38, the first marker indicating the initial health 35 status of the player and the second marker indicating the initial wealth status of the player. Assuming for purposes of illustration the first marker removed from delivery chute 38 is a 7, a suitable pegged marker will be positioned in opening 136 associated with the indicia 70 on the health board 130. Assuming that the second marker extracted is numbered 2, a suitable pegged marker will be positioned in opening 126 of wealth board 118 as 40 associated with indicia 20.

The second step of the amusement device is to extract five numbered markers from delivery chute 38 and to position one marker in indentations 140, 174, 176, 178, 180 of arms 24, 16, 18, 20 and 22. What is termed a first 45 health obligation and fulfillment is calculated from the numerals appearing on markers 46 which are positioned on arms 24, 16, 18, 20, 22 as previously mentioned. If the sum of markers 46 on arms 16, 18, 20, 22 exceeds the numeral on marker 46 on arm 24 the pegged marker will 50 be moved upwardly along strip 146 one step for each ten points difference. Assuming for purposes of illustration that the sum of markers 46 on arms 16, 18, 20, 22 is 33 and the numeral on marker 46 associated with arm 24 is 6, a difference of 27 is calculated, with the pegged marker 55 being moved upwardly along strip 146 a total of three steps. Markers 46 may then be removed from the playing arms and placed in storage area 124.

The third step of the instant amusement device is to 60 retrieve five additional spherical markers 46 from delivery chute 38 and position one on each of playing arms 16, 18, 20, 22, 24 as previously mentioned. This step is entitled a first financial obligation and fulfillment, with the sum of markers 46 on arms 16, 18, 20, 22 being totalled and the numeral of marker 46 on arm 24 being subtracted 65 therefrom. For purposes of illustration this difference is assumed to be 20 with the pegged marker on strip 142 being moved upwardly a total of two steps. Markers 46 on the playing arms are then removed and placed in storage area 124.

70 The fourth step of the instant amusement device is to retrieve three spherical markers from delivery chute 38 and position one on each of playing arms 24, 18, 20 in the indentations 140, 176, 178. The fifth step of the instant amusement device is to retrieve five markers 46 from delivery chute 38 and place one on each of playing

arms 16, 18, 20, 22, 24 as previously indicated. This is entitled a second health obligation and fulfillment with an evaluation being made as previously indicated. For purposes of illustration, it is assumed that the sum of markers placed on arms 16, 18, 20, 22 during this step is 21 with a marker numbered 4 being positioned on arm 24. Accordingly, the pegged marker on strip 146 is moved upwardly a total of two steps and resides in opening 148 adjacent indicia 2DB as seen in FIGURE 1. Indicia 2DB is a scoring indicia indicating that play is over if the player is disqualified by having previously withdrawn from distribution means 44 two delinquent or disability balls or markers. The delinquent balls or markers may be placed in indentations 156 for conveniently tabulating the number of such markers received. Since this situation has not occurred in the illustrated game, play will continue. Markers 46 on arms 16, 22 are then removed and discarded into storage area 124.

The sixth step of the instant amusement device is to remove an additional five markers from delivery chute 38. Assuming that delivery chute 38 has no markers therein, pointer 82 may be rotated, which will result in the positioning of markers 46 adjacent slot 72 of distribution means 44 and will result in the delivery of markers 46 to delivery chute 38. The five withdrawn markers are placed on each of arms 16, 18, 20, 22, 24 with a second financial obligation and fulfillment being evaluated as previously mentioned. Assuming that the total of markers placed on arms 16, 18, 20, 22 during this step exceeds the marker placed on arm 24 during this step by 16, the pegged marker associated with strip 142 will be moved upwardly a total of two steps. Markers 46 on arms 16, 22 are removed and discarded into storage area 124 while markers 46 remain on the arms 18, 20, 24. There are a total of three markers 46 on each of the arms 18, 20, 24 at this stage of the play of the device.

The seventh step of this amusement device resides in the election to discard certain ones of the markers 46 placed on the arms 18, 20 during previous steps of play in order to enhance one's chances of winning the poker evaluation of step ten and to increase the rewards in the event of winning. In accordance with the rules of the game, an arbitrarily designated factor of ambition may be exercised to discard one of the markers 46 from each of the arms 18, 20. A spherical marker is removed from indentation 128 of rating board 118, where the marker was placed prior to starting, and placed in indentation 150 of playing arm 24 as a convenient means of tabulating that the election to discard has been made. The player must forfeit ten points by moving the pegged marker up one position on strip 146. The player thereafter removes the markers 46 from arms 18, 20 which are aligned with strip 168 and replaces the removed markers with others drawn from the chute 38. This election may be made on the basis of normal poker play, e.g., one may discard low numbered markers in the indentations aligned with the strip 168 or discard odd colored markers therefrom in order to obtain a flush.

Continuing the seventh step of play, the player may elect to discard certain other of the markers 46 from the arms 18, 20 to enhance the chances of winning the evaluation of step ten. In accordance with the rules of play, an arbitrarily designated factor of talent may be exercised if the spherical marker having the talent indicia thereon has previously been withdrawn from the chute 38. As a convenient means of tabulating that the election has been made, the marker from one of the indentations 128 on rating board 118 is placed in indentation 152 of playing arm 24. The player forfeits ten points by moving the pegged marker up one move on strip 142 of playing arm 24. The player then removes marker 46 aligned with the strip 172 on each of playing arms 18, 20 and replaces each removed marker with one withdrawn from delivery chute 38. As in the case of the previously mentioned

election in the seventh step of play, this election may be made on the basis of normal poker play.

Continuing the seventh step of play, the player may elect to risk ten points from one of the playing strips 142, 146 against the possibility of doubling the rewards from the evaluation step as scored on either of rating boards 118, 130 as the player chooses. In accordance with the rules of the device, an arbitrarily designated factor of grace may be exercised by forfeiting ten points from either of strips 142, 146 by moving the pegged marker up one position. If this election is made and the evaluation of step ten results in the markers of arms 18, 20 being superior to the markers on arm 24, the marker associated with the chosen rating board is moved up two spaces rather than one. If the player should elect to double the effect of this election, he may forfeit ten points from each of strips 142, 146 thereby doubling the rewards on both rating boards 118, 130 in the event of winning the evaluation.

Continuing the seventh step of play, the player may again elect to risk ten additional points from either of the playing strips 142, 146 against the possibility of increased rewards from the evaluation step as scored on either of the rating boards 118, 130. In accordance with the rules of play, an arbitrarily designated factor of fate may be exercised by forfeiting ten points from either of strips 142, 146 by moving the pegged marker up one position. Since, in the illustrated play, the pegged marker associated with strip 146 is at the top of the strip, the marker associated with rating board 130 must be moved downwardly one position to provide additional playing positions, one movement downward on rating board 130 equaling the entire range of points available on strip 146. The eighth step of play is to withdraw three spherical markers from delivery chute 38, rotating pointer 82 if chute 38 is empty, and place one of the markers 46 on each of arms 24, 18, 20. Once again the elections of step seven may be repeated as previously indicated.

The ninth step of play is to remove three additional markers from delivery chute 38 and place them on the remaining indentations of playing arms 24, 18, 20.

The tenth step of the instant amusement device is to determine if markers 46 associated with playing arms 18, 20 are superior to markers 46 associated with playing arm 24. This is done by conventional poker evaluation of the numerals and distinctive colors of markers 46 on each of playing arms 18, 20, 24, with the distinctive colors corresponding to the suits of a conventional card deck. If markers 46 associated with playing arm 18 are superior to markers 46 associated with playing arm 24, the pegged marker associated with health rating board 130 may be moved upwardly one step. If the factor of grace has been exercised during the play of the amusement device, the pegged marker may be moved upwardly an additional step and if the factor of fate has been exercised during play, still another upward step is allowed. On the other hand, if markers 46 associated with playing board 24 are superior to markers 46 associated with playing arm 18, the pegged marker associated with health rating board 130 must be moved downwardly one step.

If markers 46 associated with playing arm 20 exceed those of playing arm 24, the pegged marker associated with wealth rating board 118 may be moved upwardly one step. If the factors of grace and fate have been exercised during play, the pegged marker of wealth rating board 118 may be moved upwardly accordingly.

The final phase of play of the instant device resides in the utilization of panel 14 and pointer 82 to select by chance what are arbitrarily designated as the reasons for failures of health and wealth. Preliminarily, markers 46 are removed from playing arms 16, 18, 20, 22, 24, with remaining markers 46 in distribution means 44 likewise being removed. Pointer 82 is spun with distinctive blade 84 being used in conjunction with indicia 76, which represent virtues and the ten commandments, to determine

the source of failure of the health and wealth pursuits. For example, if blade 84 stops at indicia 76 representing charity, this has been the source of one's failure in play. If blade 84 stops adjacent indicia 76 representing the fifth commandment, it has been the breach thereof that has resulted in failure. If this latter situation occurs, pointer 82 may be spun again to determine the dominant human temptation as indicated by indicia 76 which resulted in the commandment breach. Additional indicia may be positioned closely about hub 86 for other similar determinations.

The previously described play may be assumed to account for one decade of a player's life, with the play being continuable by moving a pegged marker from the lowest opening 148 of strip 144 on arm 24 to the next higher position and repeating the process.

It is now seen that there is herein provided an amusement device having all of the objects of this invention and others, including many advantages of great practical utility and commercial importance.

Since many embodiments may be made of the instant inventive concept, and since many modifications may be made in the embodiment hereinbefore shown and described, it is to be understood that the foregoing is to be interpreted merely as illustrative and not in a limiting sense.

I claim:

1. An amusement device comprising:
a planar horizontal base;
a spherical marker distribution means mounted on said base for randomly expelling a series of spherical markers at a predetermined point;
30 delivery chute means mounted on said base in marker exchanging relation with said distribution means for delivering said markers singly to a location on said board remote from said distribution means;

a board, mounted above said base and immediately above said distribution means;
a pointer rotatably mounted on said board;
a plurality of indicia circumferentially spaced about the axis of said pointer;
a plurality of elongate playing arms positioned on said base and extending downwardly and radially from said board, said arms being spaced from said chute means and having means for holding said spherical markers after said markers have been delivered to said remote location, said holding means comprising a plurality of marker retaining indentations for individually receiving said spherical markers.

2. The structure of claim 1 including at least one board on said base providing a series of aligned apertures and numerical indicia associated with each of said apertures, said numerical indicia representing increasing quantities from one end of said series to the other, said board being positioned between and juxtaposed to adjacent playing arms to define with said arms and said base a marker storage area.
